UNITED STATES PATENT OFFICE

JOSEPH K. HEYMAN, OF CHICAGO, ILLINOIS, ASSIGNOR TO RELIANCE MANUFACTURING COMPANY, OF CHICAGO, ILLINOIS, A CORPORATION OF ILLINOIS

CLOTHING

Application filed July 31, 1930. Serial No. 471,920.

This invention relates to clothing. It is particularly adapted to be employed in athletic clothing such as trunks or running breeches, and in underclothing commonly called shorts.

An object of this invention is the provision of a garment of the kind above identified having a self-adjusting hip and waist.

Another object is the provision of a garment embodying a hip construction permitting expansion to accommodate activity of the wearer without the use of pleating at the hips.

A further object is the provision of such a garment embodying a self-adjusting waist which is rugged of construction while being simple and economical to manufacture.

In the accompanying drawings:

Figure 1 is a plan view of one side of a pair of shorts incorporating my invention and shown as they appear lying flat on a table;

Figure 2 is an enlarged fragmentary plan view similar to Figure 1 showing the hip and belt portions expanded as when being worn;

Figure 3 is a fragmentary plan view of the belt portion showing the band element and the lining stitched together at one edge and lying flat with reinforcing element secured to the band element;

Figure 4 is a view of that shown in Figure 3 and illustrating a further step in the construction of a garment with the band element folded upon the lining and with the elastic element inserted and secured in position;

Figure 5 is a view similar to Figure 4 but showing in addition the body portion of the garment attached to the waist band and illustrating the elastic in contracted position;

Figure 6 is a longitudinal section taken on the line 6—6 of Figure 5; and

Figure 7 is a longitudinal section taken on the line 7—7 of Figure 4.

My invention as embodied in the accompanying drawings comprises a body portion 5

and a waist portion 6 stitched thereto around the upper edge of the body portion. The body portion is preferably constructed of relatively non-elastic material having a substantially V-shaped element 8 positioned in the region of the hip and stitched to the edges of the members 9 and 10 forming the body portion at 11 and 12 as shown in Figure 2. The element 8 is preferably of knitted or other relatively elastic material which is adapted to readily conform to the shape of the hip without the necessity of the making of pleats in the vicinity of the hips at the waist line.

The waist portion 6 comprises a lining 14 stitched adjacent its upper edge at 15 to a band element 16. A reinforcing element 17 is placed upon the band element 16 as shown in Figure 3 and both of the elements have formed therein spaced openings 18 of the button hole type which are preferably reinforced about their edges by suitable stitching which permanently secures the reinforcing element to the band element.

The next step in the construction of the waist portion consists in folding the band element with the reinforcing element onto the lining in the position shown in Figure 4. An elastic member 21 having its ends tapered as shown at 22 is laid upon the band element 75 and its tapered ends are inserted through the spaced openings 18 and secured in position by a triangular bar stitching 23 which stitching extends through the lining, the elastic member, and the reinforcing and band elements as a unit, as clearly shown in Figures 6 and 7.

Although the openings 18 through the band element reduces its strength by reducing its cross section, this weakness is overcome by 85 the addition of the reinforcing element 17 which is not only secured to the band element by the stitching about the openings 18 but is permanently secured through and to the lining 14 by the bar stitching 23 whereby 90

the waist band is actually capable of withstanding greater stress at the hips than at other points. When the elastic member 21 is expanded as it normally will be when the 5 garment is properly fitted on the wearer, the knitted portion 8 is in its natural or unexpanded stage which is then capable of expanding and contracting to accommodate the activity of the wearer and at the same time 10 aiding to retain the garment snugly in position.

By employing this invention the manufacture of clothing of this type is greatly facilitated. The various parts are assembled in 15 place one at a time and permanently secured by stitching before applying other parts. It is unnecessary therefore to hold several unattached elements or portions of the garment in place while they are being stitched together as a unit.

It will be understood by those skilled in the art that the specific embodiment of my invention illustrated in the accompanying drawings is susceptible to modification without departing from the spirit of my invention and I desire therefore to avail myself of such modifications as may come within the scope of the appended claims.

I claim as my invention:

30 1. In an article of the class described, a body portion, a waist band portion comprising a non-elastic band element having spaced openings therein, a reinforcing element lying along one side of the band element with its ends extending beyond the spaced openings and having spaced openings therein, the edge of which coincide with the edges of the openings in the band element, an elastic member lying along said band element with its ends extending through the spaced openings in the band element and in the reinforcing element, and fixedly secured to said elements beyond the openings.

45 2. In an article of the class described, a body portion, a waist band portion comprising a non-elastic band element having spaced openings therein, and a lining for said band element secured thereto along its edges, a reinforcing element interposed between said band and said lining and secured thereto, an elastic member lying along said band element between the spaced openings and having its ends extending through the openings into the space between the lining and the 50 band element and secured to the opposite side of the band element.

55 3. In an article of the class described, a body portion, a waist band portion comprising a non-elastic band element having spaced openings therein, and a lining for said band element secured thereto along its edges, a reinforcing element interposed between said band and said lining and secured thereto, an elastic member lying along said band element between the spaced openings and hav-

ing its ends extending through the openings into the space between the lining and said reinforcing element and secured beyond the openings by bar stitching through the band and lining as a unit.

70 4. In an article of the class described, a body portion, a waist band portion comprising a non-elastic band element having spaced openings therein, and a lining for said band element secured thereto along its edges, a reinforcing element lying along one side of the band element with its ends extending beyond the spaced openings and having spaced openings therein, the edges of which coincide with the edges of the openings in the band element, an elastic member lying along said band element with its ends extending through the spaced openings in the band element and in the reinforcing element into the space between the lining and the band element and fixedly secured to said elements beyond the spaced openings.

75 5. In an article of the class described, a body portion, a waist band portion comprising a non-elastic band element having spaced openings therein, and a lining for said band element secured thereto along its edges, a reinforcing element lying along one side of the band element with its ends extending beyond the spaced openings and having spaced openings therein, the edges of which coincide with the edges of the openings in the band element, an elastic member lying along said band element with its ends extending through the spaced openings in the band element and in the reinforcing element into the space between the lining and the band element and secured beyond the openings by bar stitching through the band element and lining as a unit.

80 6. In an article of the class described, a body portion, a waist band portion comprising a non-elastic band element having spaced openings therein, and a lining for said band element secured thereto along its edges, a reinforcing element lying between said band element and said lining with its ends extending beyond the spaced openings and having spaced openings therein, the edges of which coincide with the edges of the openings in the band element, an elastic member lying along said band element with its ends extending through the spaced openings in the band element and in the reinforcing element into the space between the lining and the reinforcing member, and fixedly secured to said elements beyond the spaced openings.

85 7. In an article of the class described, a body portion, a waist band portion comprising a non-elastic band element having spaced openings therein, and a lining for said band element secured thereto along its edges, a reinforcing element lying between said band element and said lining with its ends extending beyond the spaced openings and having

spaced openings therein, the edges of which coincide with the edges of the openings in the band element, an elastic member lying along said band element with its ends extending through the spaced openings in the band element and in the reinforcing element into the space between the lining and the reinforcing member, and secured to the lining and to said elements by stitching through the same as a unit.

In witness whereof, I hereunto subscribe my name this 25th day of July, 1930.

JOSEPH K. HEYMAN.
